UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

ELECTRIC-LOCOMOTIVE BED.

1,293,906.

Specification of Letters Patent. Patented Feb. 11, 1919.

Application filed May 9, 1918. Serial No. 234,124.

To all whom it may concern:

Be it known that I, HARRY M. PFLAGER, a citizen of the United States, residing at St. Louis, Missouri, have invented a certain 5 new and useful Improvement in Electric-Locomotive Beds, of which the following is a full, clear, and exact description, such as will enable others skilled in the art to which it appertains to make and use the same, 10 reference being had to the accompanying drawings, forming part of this specification.

My invention relates generally to electric locomotives, and more particularly to a bed or frame therefor, said bed or frame 15 being carried by the locomotive wheels and serving as a support for the body of the locomotive.

In connection with my invention it will be understood that to a large extent it is 20 the present practice to construct locomotive beds or frames in separately formed pieces and to rigidly connect said pieces by means of bolts, rivets and the like. This method of manufacture has certain disadvantages, 25 for instance, the cost of production of the separate parts, the time and labor involved in fabrication, and further, for the reason that the strains and consequent vibration developed while the bed or frame is in service 30 tends to loosen the joints between the assembled parts, thereby materially decreasing the strength and stability of the frame and also destroying the alignment of various brackets and bearings which receive certain parts necessarily associated with and 35 carried by the bed or frame.

The principal object of my invention is to 40 overcome the objectionable features just noted by casting the entire bed or frame in a single piece and forming integral therewith a number of essential parts, which construction produces a very strong, rigid and substantial bed which in service will resist to a relatively high degree all strains to 45 which it is ordinarily subjected and which bed will not be affected by the constant vibration and service shocks which it may receive while in use.

By my improved construction I am able 50 to produce with practically the same amount of metal now used in a fabricated structure, a bed or frame which has much greater strength than said fabricated structure, and likewise it is possible to produce a frame

having the requisite strength with comparatively less metal and consequently less weight than is required in an assembled structure.

With the foregoing and other objects in view, my invention consists in certain novel 60 features of construction and arrangement of parts, hereinafter more fully described and claimed, and illustrated in the accompanying drawings, in which—

Figure 1 is a top plan view of a locomotive bed of my improved construction.

Fig. 2 is a side elevational view of the bed.

Fig. 3 is an enlarged top plan view of the 70 lefthand portion of the bed.

Fig. 4 being an elevational view of said lefthand portion.

Fig. 5 is an enlarged top plan view of the right-hand portion of the bed, and

Fig. 6 a side elevational view of said 75 righthand portion.

Fig. 7 is an enlarged cross section taken approximately on the line 7—7 of Fig. 1.

Fig. 8 is an enlarged cross section taken approximately on the line 8—8 of Fig. 1. 80

Fig. 9 is an enlarged cross section taken approximately on the line 9—9 of Fig. 1.

Fig. 10 is an enlarged cross section taken approximately on the line 10—10 of Fig. 1.

Fig. 11 is an enlarged cross section taken 85 approximately on the line 11—11 of Fig. 1.

Fig. 12 is an enlarged detail section taken approximately on the line 12—12 of Fig. 1.

Fig. 13 is an enlarged detail section taken approximately on the line 13—13 of Fig. 1. 90

Fig. 14 is an enlarged detail section taken approximately on the line 14—14 of Fig. 1.

Referring by numerals to the accompanying drawings which illustrate a practical embodiment of my invention, 10—10 designate the side members of the bed or frame, which members are arranged in parallel relation and are substantially box-shape in cross section, that is, each member comprises a pair of spaced vertically disposed side walls, a top plate and a bottom plate. Formed integral with these side members and arranged at suitable distances apart are depending pairs of pedestals 11, the spaces 12 between which are adapted to receive the 100 usual journal boxes.

The top plates of the side members 10 immediately over the pairs of pedestals 11 are

- provided with elongated openings 13 for the accommodation of the semi-elliptic springs (not shown) which are mounted on the journal boxes disposed between the pedestals.
- 5 By virtue of this construction, portions of the side members 10 above and immediately adjacent to the pairs of pedestals are substantially U-shaped in cross section. The bottom plates of the side members below the
- 10 openings 10 and to the sides of the pedestals 11 are provided with relatively short slots 14 which are adapted to receive the lower legs of spring saddles (not shown) which are associated with the springs disposed
- 15 upon the journal boxes.

The forward ends of the side members 10 are connected by a transversely disposed integrally formed end sill 15 which is preferably channel-shape in cross section with

20 the horizontal flanges inwardly presented. Connecting the side members 10 a short distance to the rear of end sill 15 is an integrally formed transverse member 16, preferably of box-shape in cross section and dis-

25 posed between this transverse member and end sill 15 are integrally formed longitudinally disposed members 17, preferably of I-beam shape in cross section and slightly inclined so that they gradually diverge from

30 said end sill toward transverse member 16.

Formed on top of transverse member 16 at points equidistant from the transverse center thereof are side bearing pads 18 and formed through the top plate of transverse member

35 immediately outside these pads are openings 19 which are for the accommodation of the brake cylinder levers (not shown).

Formed in the center of transverse member 16 is a front draw-bar pocket 20, the

40 same being open at its front end and formed in the plates above and below this pocket are apertures 21, preferably bushed and which are adapted to receive the pin or bolt which pivotally connects the front draw-bar

45 to the bed or frame.

Depending from the underside of transverse member 16 are integrally formed brackets 22, the same serving as bearings for the brake cylinder lever fulcrum (not shown). Formed integral with the side members 10 adjacent to the ends of transverse member 16 are integrally formed depending brackets 23, the lower portions of which are provided with suitable bearings

50 24 which are adapted to receive the equalizer fulcrums (not shown).

Formed integral with the side members 10 between end sill 15 and transverse member 16 are depending brackets 25, the same being

55 arranged in pairs and serving as lead truck equalizer guides. Formed integral with the rear side of transverse member 16 is a rearwardly projecting bracket 26 which serves as a motor support.

60 Located a short distance to the rear of

transverse member 16 and integrally connected to side members 10 at points between the pairs of pedestals 11 for the journal boxes of the first and second axles, is a transversely disposed center guide transom 27, 70 the same being of any desired cross sectional shape and formed on top of side members 10 at the ends of this transom are side bearing pads 28. Formed integral with the front and rear walls of this transom 27 are outwardly projecting brackets 29, the same serving as motor supports. Formed on the underside of this transom 27 and at points adjacent to side members 10 are depending brackets 30, preferably arranged in pairs, 80 said brackets serving as bearings for the fulcrums of the brake hanger levers (not shown).

Formed in the side walls of members 10 at points adjacent to the ends of transom 27 85 are bearings 31 which are adapted to receive the fulcrums of equalizers (not shown). Transversely disposed between side members 10 a short distance to the rear of transom 27 and at a point between the pedestals for the journal boxes of the second and third axles 90 is an integrally formed motor supporting transom 32, the same being provided on both front and rear sides with outwardly projecting motor supporting brackets 33. 95

Depending from the side members 10 at points near the ends of this transom 32 are brackets 34 which are adapted to serve as bearings for brake lever fulcrums (not shown). The rear ends of side members 10 100 are connected by an integrally formed rear end sill 35, preferably of channel-shape in cross section with its horizontally disposed flanges inwardly presented and arranged a short distance in front of this end sill is an integrally formed transversely disposed transom member 36. This last mentioned member is preferably channel-shape in cross section with its horizontally disposed flanges rearwardly presented and connecting the central portions of end sill 35 and transom 36 is a longitudinally disposed member 37, preferably of I-beam shape in cross section. 110

Formed integral with the underside of member 37 adjacent the point where the same joins the transom 36 is a housing 37^a, the chamber within which serves as a rear draw-bar pocket 37^b and the plates of the housing above and below this pocket are 120 provided with openings 37^c, preferably bushed which are adapted to receive the pin or bolt which pivotally connects the rear draw-bar to the bed or frame.

Formed on top of transverse member 36 125 are side bearing pads 38 and formed integral with the front side of said transverse member are forwardly projecting motor supporting brackets 39. Depending from the members 10 at points near and slightly in 130

front of transverse member 36 are brackets 40, the same serving as bearings for the fulcrums of equalizers (not shown).

Formed integral with the underside of transverse member 36 are depending brackets 41, the same serving as fulcrums for brake hanger levers (not shown). Formed integral with the side members 10 at points between end sill 35 and transverse member 36 are depending brackets 42, arranged in pairs and performing the functions of guides for motor truck equalizers (not shown).

An electric locomotive bed of my improved construction combines great strength and rigidity with minimum weight, can be easily and cheaply produced by reason of the fact that it can be readily cast in a single piece and the elimination of joints in the bed or frame overcomes structural weaknesses which invariably develop when an assembled or fabricated structure is subjected to service strains and vibrations.

A one-piece casting can be produced in much less time and with less labor and expense than a frame which is built up from a number of structural shapes and special castings which are united by bolts, rivets and the like, for the assembling of parts necessarily involves considerable machine-work and likewise involves considerable time and labor in the formation of rivet holes and the setting of the securing means, such as bolts, rivets or the like.

It will be readily understood that minor changes in the size, form and construction of the various parts of my improved locomotive bed may be made and substituted for those herein shown and described, without departing from the spirit of my invention, the scope of which is set forth in the appended claims.

I claim:

1. An electric locomotive bed having integrally connected side members having pedestals, and portions of said side members above and adjacent to said pedestals being substantially U-shape in cross section for the accommodation of springs and spring supporting members.

2. An electric locomotive bed having integrally connected side members, portions of which are substantially U-shape in cross section, pedestals depending from said members below said U-shaped portions, and the bottom plates of the U-shaped portions of said side members being provided with openings adapted to receive parts of spring saddles which support springs positioned in said U-shaped portions.

3. An electric locomotive bed having a pair of integrally connected side members, portions of which are substantially U-shape in cross section for the accommodation of springs, and the bottom plates of said U-

shaped portions being provided with openings adapted to receive parts of the spring securing means.

4. An electric locomotive bed having a pair of integrally connected side members, portions of which are substantially U-shape in cross section for the accommodation of springs, and the bottom plates of said U-shaped portions being provided with a pair of openings adapted to receive parts of the spring securing means.

5. An electric locomotive bed comprising a pair of integrally connected side members, portions of which are substantially U-shape in cross section to accommodate springs and spring securing means and other portions being box-shape in cross section.

6. An electric locomotive bed having a pair of integrally connected side members, and motor truck equalizer guides formed integral with said side members.

7. An electric locomotive bed having a pair of integrally connected side members, and lead truck equalizer guides formed integral with said side members.

8. An electric locomotive bed comprising a pair of integrally connected side members, motor truck equalizer guides formed integral therewith, lead truck equalizer guides formed integral with said side members, and pairs of pedestals integral with said side members.

9. An electric locomotive bed having a pair of integrally connected side members, a front end sill and a rear end sill, a transverse member located a short distance to the rear of the front end sill and connecting said side members, equalizer fulcrum brackets depending from the side members between the front end sill and adjacent transverse member, and longitudinally disposed members connecting said front end sill and adjacent transverse member.

10. An electric locomotive bed having a pair of integrally connected side members, a front end sill and a rear end sill, a transverse member located a short distance to the rear of the front end sill and connecting said side members, and equalizer fulcrum bearings on said side members adjacent to the ends of said transverse member.

11. An electric locomotive bed having a pair of integrally connected side members, a front end sill and a rear end sill, a transverse member located a short distance to the rear of the front end sill and connecting said side members, and there being openings in said transverse member, which openings are adapted to accommodate the brake cylinder lever.

12. An electric locomotive bed having a pair of integrally connected side members, a front end sill and a rear end sill, a transverse member located a short distance to the rear of the front end sill and connecting

- said side members, and a motor supporting bracket on said transverse member.
13. An electric locomotive bed having a pair of integrally connected side members, 5 an integrally formed center guide transom, motor supporting brackets on both sides of said transom, and side bearing pads on top of the side members adjacent to the ends of said transom.
- 10 14. An electric locomotive bed having a pair of integrally connected side members, an integrally formed center guide transom, and motor supporting brackets on said center guide transom.
- 15 15. An electric locomotive bed having a pair of integrally connected side members, an integrally formed center guide transom, and side bearing pads on said side members adjacent to the ends of the center guide 20 transom.
16. An electric locomotive bed having a pair of integrally connected side members, an integrally formed center guide transom, and bearings on said center guide transom 25 for the fulcrums of brake hanger levers.
17. An electric locomotive bed having a pair of integrally connected side members, an integrally formed center guide transom, and said side members being provided adjacent to the ends of said center guide transom with bearings for equalizer fulcrums.
- 30 18. An electric locomotive bed having a pair of integrally connected side members, a plurality of transoms formed integral with 35 said side members, and pairs of motor supporting brackets on said transoms.
19. An electric locomotive bed having a pair of integrally connected side members, an integrally formed motor supporting 40 transom, and motor supporting brackets on said transom.
20. An electric locomotive bed having a pair of integrally connected side members,
- an integrally formed motor supporting transom, and bearings on said motor supporting transom for the fulcrums of the brake hanger levers. 45
21. An electric locomotive bed having a pair of integrally connected side members, a transverse member formed integral with 50 said side members near their rear ends, and side bearing pads on said transverse member.
22. An electric locomotive bed having a pair of integrally connected side members, a transverse member formed integral with 55 said side members near their rear ends, side bearing pads on said transverse member, and a motor supporting bracket on said transverse member. 60
23. An electric locomotive bed having a pair of integrally connected side members, a transverse member formed integral with 65 said side members near their rear ends, side bearing pads on said transverse member, and bearings on said transverse members for brake lever fulcrums.
24. An electric locomotive bed having a pair of integrally connected side members, a transverse member formed integral with 70 said side members near their rear ends, side bearing pads on said transverse member, and brackets depending from said side members adjacent to the ends of said transverse member, which brackets are provided with bearings for equalizer fulcrums. 75
25. An electric locomotive bed comprising a pair of side members, a front end sill, a rear end sill, a transverse member adjacent to the front end sill, a transverse member 80 adjacent to the rear end sill, a center guide transom, and a motor supporting transom, all of which parts are integrally formed.

In testimony whereof I hereunto affix my signature this 4th of May, 1918.

HARRY M. PFLAGER.
